CLAIM

I claim the ornamental design for a pinball game board, as shown and described.

DESCRIPTION

FIG. 1 is a Perspective view of a pinball game board showing my new design;

FIG. 2 is a Top view thereof wherein the support element projecting from the rear in FIGS. 4-6 is shown in an alternate retracted position;

FIG. 3 is a Bottom view thereof;

FIG. 4 is a Right-side view thereof;

FIG. 5 is a Left-side view thereof;

FIG. 6 is a Front view thereof; and,

FIG. 7 is a Back view thereof.
